UNITED STATES PATENT OFFICE.

GEORGE E. BISHOP, OF CLEVELAND, OHIO.

AUTOMOBILE DOOR HANDLE.

Application filed December 14, 1923. Serial No. 680,608.

To all whom it may concern:

Be it known that I, GEORGE E. BISHOP, a citizen of the United States, resident of Cleveland, county of Cuyahoga, and State of Ohio, have invented new and useful Improvements in Automobile Door Handles, of which the following is a specification, the principle of the invention being herein explained and the best mode in which I have 10 contemplated applying that principle, so as to distinguish it from other inventions.

My invention relates to door handles and particularly to apparatus of this kind designed to be applied to Ford or other automobiles provided with only an inside handle. Furthermore, certain types of my invention are designed to serve as standard equipment for door handles in the original manufacture of any automobile.

20 The annexed drawing and the following description set forth in detail certain means embodying my invention, such means constituting, however, but a few of the various forms in which the principle of the invention may be applied.

In said annexed drawing:

Figure 1 represents a broken inside elevation of the door of a Ford automobile equipped with one type of standard Ford 30 inside door handle to which has been added one form of my invention designed to serve said car both as an inside and outside handle, in conjunction with the standard inside handle;

Figure 1^a is an outside elevation of the elements shown in Figure 1;

Figure 2 represents a transverse horizontal section, taken in the plane indicated by the line II—II, Figure 1;

Figure 3 is an elevation of an inside arm forming one of the elements shown in Figures 1 and 2;

Figure 4 is an elevation of a transverse door bolt forming one of the elements shown 45 in Figures 1 and 2;

Figures 5 and 5^a are views respectively similar to Figures 1 and 1^a, and showing my invention applied to a type of door equipped with another form of standard inside handle;

Figure 6 is a transverse horizontal section, taken in the plane indicated by the line VI—VI, Figure 5;

Figure 7 is a broken transverse horizontal section, upon a reduced scale, illustrating the application of one type of my invention

in which the same serving as an outside handle only, acts upon the latch bolt through the medium of a standard latch dog;

Figure 8 is a plan of the door handle and outside door plate or escutcheon shown in Figure 7;

Figure 9 is an elevation, taken from the plane indicated by the line IX—IX, Figure 8;

Figure 10 is a broken transverse horizontal section showing an application of my invention to a sheet metal door, the type of invention herein shown serving as standard equipment for both outside and inside 70 handles without the aid of any other inside handle;

Figure 11 is an elevation of two assembled handles for a sheet metal door, differing in some particulars from the assembly shown 75 in Figure 10; and

Figure 12 is an elevation of a bushing shown in Figure 11, the scale of Figures 8, 9, 10, 11 and 12 being substantially the same as that of Figure 7.

Referring particularly to Figures 1, 2, 3 and 4, there is therein shown a fragmentary section of an automobile door 1 the same being equipped with one of the standard Ford types of inside handles 2 which, when 85 it is actuated, will, as is well understood, travel in the door slot 11 to retract the latch bolt (not shown) in order that the door 1 may be opened. The usual latch spring, upon the release of the handle 2, returns said handle to its original position, as is also well understood.

To this standard equipment I add inside and outside door plates or escutcheons 3 and 4, respectively, which are intersected by a cylindrical carriage bolt 5 having a head 5¹ at its outer end and an exteriorly threaded portion 5² at the inner end and which passes transversely through the door 1. Secured upon the inner portion 5² of the bolt 5 is an arm 6 held in an inclined position substantially as shown in Figure 1, the upper end 6¹ of which extends above the door 1. It is not particularly important that this upper end 6¹ should thus extend above the door 1 and perhaps many operators of cars would prefer that the same

would not show so that, if desired, the same could be eliminated by shortening the upper end of the arm 6, without affecting the operation of my invention. This arm 6 is somewhat spaced from the inner face of the door 1 by means of a nut 7 threaded upon the

inner part of the portion 5² of the bolt 5. Secured to the bolt 5 adjacent the head 5' is an outside handle 8, of the design plainly shown in Figure 2, which is rigidly secured 5 to the bolt 5 in the following manner: The bolt 5 is provided with a shoulder 9, plainly indicated in Figure 4, and after the bolt 5 is passed through the section 8' of the handle 8, this shoulder 9 is upset substantially in the 10 section 10, Figure 2, so as rigidly to secure together the bolt 5 and the section 8'. I direct particular attention to the formation of the handle 8, the same being substantially U-shaped having one leg of the U substantially longer than the other, the construction being such as to enable the handle to be readily and conveniently grasped and operated, there being provided plenty of finger room and ample leverage. Both ends 15 of the standard handle 2 lie adjacent the inner arm 6. It is evident from this description of the elements shown in Figures 1 to 4 that a pull or push upon the upper end 6' of the inner arm 6 will actuate the handle 2 in the door slot 11 and retract the latch bolt. When it is desired to open the door 1 from the outside, a twist upon the handle 8 will through the medium of the bolt 5 cause the arm 6 to push upon the lower end 20 of the standard handle 2, or upon the upper end of the latter, dependent upon whether the outside handle 8 is twisted upwardly or downwardly, thus retracting the latch bolt. After either of these operations, the standard latch spring will return the standard handle 2 to its original position and thus will straighten up the arm 6 and the outer door handle 8.

Referring to the construction shown in 40 Figures 5 and 6, another type of standard inside handle 12 is shown adapted to be operated in the slot 13. For this construction I have provided an inside arm 15 spaced by a nut 16 from the inside door plate 14. This 45 plate 14 is considerably wider than the plate 3 shown in Figure 1 and is held by two screws 14' adjacent the door edge of the escutcheon instead of by two end screws 3', as shown in Figure 1, the other end of the 50 plate 14 being intersected and held by the bolt 17 to which the inner arm 15 is secured. The bolt 17 is provided at the outer end with a head 17' and is held at the inner end by the nut 17². Intersecting the outer face of 55 the door 1 in this type of construction is a bushing 18 which is driven into the door for a tight fit and in which the bolt 17 turns. In this form of construction the upper end 15' of the inner arm 15 is inclined substantially as shown in Figure 5 so as to bring a 60 considerable section 15² of the arm 15 adjacent the standard handle 12. When the member 15' is actuated in either direction, it will push the standard handle 12 in the 65 slot 13 to retract the latch bolt. This will

apply either when the outer handle 8 is actuated or the inner arm 15. The construction of the arm 15 is such that whether the upper end 15' pushes against the handle 12 in opening the door, or whether the lower central portion 15² pushes against the handle 12, the contacting surfaces of members 12 and 15 are amply large to provide satisfactory operation. In either event, the handle 12, after the release of the arm 15 or the outer handle 8, will be actuated back into normal position by the standard latch spring (not shown).

In Figures 7, 8 and 9 I have illustrated an outside handle 24 only. In this construction I show a dog 22 adapted to actuate a door bolt (not shown). This is the same bolt that is actuated by the standard inside handle 2 or 12 in the applications shown in Figures 1 and 5. Unlike the constructions of Figures 1 and 5 wherein the outer handle acts through an inner arm, in the construction shown in Figure 7, the outer handle acts on the latch bolt through the standard dog 22. The outer handle 24 is formed with a transverse bolt 25, of rectangular cross-section, as indicated in Figure 9, to which is fastened a bushing 26 by means of a pin 28 90 interiorly of an outside door plate 27. During the actuation of the outside handle 24 to 95 retract the door bolt the stress is all exerted upon the holding prongs 23 of the outside plate 27 so that there is no danger of the section 25 of the handle becoming loosened or pulling out.

I wish to direct particular attention to the fact that the forms of handles 8 and 24 are not only conveniently operated but, from a manufacturing standpoint, present definite advantages in that the same can be made 105 from cold rolled brass requiring very little of the polish and finish that it is necessary to make upon the ordinary cast handle. I also claim novelty for the open-ended handle of substantially U-shaped construction having an outer grip side 8, a substantially parallel comparatively short inner side 8' secured to a transverse door member 5 or 25, and an intermediate connecting portion 8² of a length sufficient to furnish ample 110 finger space between the portion 8 and the door.

Referring to the compound construction shown in Figure 10, and adapted to serve both as an outside handle 24 and an inside handle 30, the same is designed to serve as original equipment for sheet metal doors 21. I direct attention to the outside bushing 29 and the inside bushing 32. These bushings are fitted to the door 21 by a driving fit and the rectangular section 25 of the handle 24 turns in these bushings and contacts with the same at its four edges. An inner handle 30 is held to the bolt section 25 by means of an inside nut 31, plainly shown in Figure 10, 120

The assembling is somewhat different in Figures 11 and 12 wherein two bushings 34 and 35 which receive an intermediate rectangular dog actuating member 33 are fitted in the door and the member 33 is brazed to the inner portions of outside and inside handles 24 and 30, respectively. The formation of one of these bushings 34 is plainly shown in Figure 12.

10 What I claim is:

1. A vehicle door handle comprising in combination with a door having a standard spring-latch and inside latch-retracting handle; of a rotatable member supported by the 15 door and extending transversely thereof; an outside handle secured to said member; and an operating arm secured to said member adjacent said inside handle, the latter extending both above and below the connection of said member and arm so as to be actuated upon the movement of the outside handle or the operating arm in either direction.

2. A vehicle door handle comprising in combination with a door having a standard 25 spring-latch and inside latch-retracting handle; of a member rotatably mounted in the door and extending exteriorly thereof; an outside handle secured to said member; and means adapted to retract the latch upon the 30 actuation of said outside handle, said means consisting of a movable inside arm secured intermediate its ends to said rotatable member and positioned adjacent said standard 35 inside handle at points both above and below said rotatable member.

3. A vehicle door handle comprising in combination with a door having a standard 40 spring-latch and inside latch-retracting handle; of a member rotatably mounted in the door and extending exteriorly thereof; an outside handle secured to said member; and means adapted to retract the latch upon the 45 actuation of said outside handle, said means consisting of a movable inside arm secured intermediate its ends to said rotatable member, and also intermediate the ends of said standard inside handle, both ends of the latter lying adjacent said inside arm.

50 4. A vehicle door handle comprising in combination with a door having a standard spring-latch and inside latch-retracting handle; of a bolt rotatably mounted in the door

and extending exteriorly thereof; an outside handle secured to said bolt; and means 55 adapted to retract the latch upon the actuation of said outside handle, said means consisting of a movable inside arm secured intermediate its ends to said bolt and inclined at its top end from the edge of the door, 60 said standard inside handle being movable away from the edge of the door to open the latter and lying both above and below said bolt, said inside arm being positioned adjacent both ends of said standard handle and 65 intermediate the latter and the edge of the door.

5. The combination with a vehicle door and a spring-latch and latch-operating mechanism; of a cold rolled metallic vehicle 70 door handle having an outer grip portion; a bushing secured in the door; an extension of the door portion of said handle intersecting said bushing and said door; means holding said extension in the door; 75 and means connecting said extension and said latch-operating mechanism.

6. The combination with a vehicle door and a spring-latch and latch-operating mechanism; of a cold rolled metallic vehicle 80 door handle having an outer grip portion, a door portion, and an intermediate connecting portion of a length sufficient to furnish ample finger space between the grip portion and the door; a bushing secured in the 85 door; an extension of the door portion of said handle intersecting said bushing and said door; means holding said extension in the door; and means connecting said extension and said latch-operating mechanism. 90

7. The combination with a vehicle door and a spring-latch and latch-operating mechanism; of door handle means, comprising outer and inner grip members, bushings secured respectively in the outer and 95 inner faces of the door, an intermediate door-intersecting member formed integrally with one of said grip members and rotatably mounted in said bushings; means securing said other grip member upon said intermediate member; and means connecting said intermediate member and said latch-operating mechanism. 100

Signed by me this 1st day of December, 1923.

GEORGE E. BISHOP.
